Richard Amberton, London, England

Application March 3, 1942, Serial No. 106,067
In Great Britain May 13, 1941

Term of patent 14 years

To all whom it may concern:

Be it known that I, Richard Amberton, a British subject, residing at 32 Queen Victoria Street, London, E. C. 4, England, have invented a new, original, and ornamental Design for a Combined Chair and Storage Cabinet, of which the following is a specification, reference being had to the accompanying drawing, forming part thereof.

Figure 1 is a perspective view of a combined

chair and storage cabinet, showing my new design;

Figure 2 is a side elevational view; and
Figure 3 is a top plan view thereof.

I claim:

The ornamental design for a combined chair and storage cabinet, as shown.

RICHARD AMBERTON.
